(57) CLAIM

The ornamental design for a condiment holder for umbrella pole, as shown and described.

DESCRIPTION

FIG. 1 is a front elevational view of a condiment holder for umbrella pole of the present invention, the left, right and rear views being a mirror image thereof;

FIG. 2 is a top plan view of the condiment holder for umbrella pole of FIG. 1;

FIG. 3 is a bottom plan view of the condiment holder for umbrella pole of FIG. 1; and,

FIG. 4 is a top, front perspective view of the condiment holder for umbrella pole of FIG. 1.

The broken lines showing an umbrella pole in FIG. 4 are for illustrative purposes only and form no part of the claimed design.
